UNITED STATES PATENT OFFICE.

HOWARD THURSTON, OF COSCOB, CONNECTICUT.

APPARATUS FOR PRODUCING STAGE EFFECTS.

1,104,846.

Specification of Letters Patent. Patented July 28, 1914.

Application filed December 8, 1913. Serial No. 805,313.

To all whom it may concern:

Be it known that I, HOWARD THURSTON, residing at Cos Cob, in the county of Fairfield and State of Connecticut, a citizen of the 5 United States, have invented or discovered certain new and useful Improvements in Apparatus for Producing Stage Effects, of which improvements the following is a specification.

10 The invention described herein relates to apparatus for producing stage effects and has for its object the combination of vehicles moving along a portion of a track arranged on the stage with means whereby 15 an illusory appearance of the same vehicles moving over another portion of the track may be produced.

The invention is hereinafter more fully described and claimed.

20 In the accompanying drawings forming a part of this specification Figure 1 is a front view showing a portion of a race track on the stage and a curtain having a landscape painted thereon and showing in outline 25 a portion of the race track; Fig. 2 is a sectional plan view on a plane indicated by the line II—II Fig. 1; Fig. 3 is a sectional elevation on a plane indicated by the line III—III Fig. 2; Fig. 4 is a view similar to 30 Fig. 1 showing an accident occurring to one of the cars; Fig. 5 shows a portion of a moving picture film; Fig. 6 shows in front elevation and in section a form of apparatus adapted to be used in lieu of the moving 35 picture apparatus for producing the illusory movements of the vehicles; Fig. 7 shows in longitudinal and transverse sections a modification of the apparatus shown in Fig. 6, and Fig. 8 shows in plan and section 40 a suitable manner of connecting the operating rods to the cars.

While an automobile race has been selected for illustrating my improvements, it will be readily understood by those skilled 45 in the art, that the apparatus can be employed for depicting the movements of other vehicles and also races between men and animals and hence the term "object" is used herein in its broadest sense and as including 50 vehicles of the auto-type, bicycles, vehicles drawn by horses, men and animals, and boats.

In the practice of my invention a portion 1 of a track which may be used for vehicles 55 moving on land or in the form of a tank for

motor boats, etc., is arranged on the stage near the front thereof and extends from behind the wing 2 on one side of the stage to a point behind the opposite wing 2^a. As shown in Fig. 2 the portion 1 of the track 60 is a part of a circular track, so that objects passing back of 2^a, can be moved around back of the drop curtain 4 along the portion 3 of the circular track and caused to move out again from behind the wing 2. At the beginning of a race, say a race between automobiles, full sized operative machines are driven by chauffeurs from behind the wing 2 along the portion 1 of the track and pass out behind and off the track behind the 70 wing 2^a. Each of the real autos are rendered distinctive from the others by color or by mark as numerals, 5, 7, 9. In addition to the real machines, skeleton dummies constructed to closely resemble the real machines and having similar distinctive marks 75 are arranged behind the drop curtain 4, and as each real machine passes behind the wing 2^a the dummy corresponding thereto is started along the portion 3 of the track. 80 These dummies which have real auto wheels set at such an angle as to move without steering along the circular track may be shifted by any suitable means. In the construction shown a vertical shaft 8 is secured 85 on the stage in the center of the circular track and on this shaft are mounted sleeves 9 provided with radial ears 10, to which the inner ends of arms 11 are pivotally connected. The outer ends of these arms are formed 90 by hinged sections 12 which are detachably connected to the respective cars.

It is desirable to produce the best effects that the dummy should pass at a very high speed along the portion 1 of the track, and hence the portion 3 of the track is inclined 95 upwardly from the point *a* just behind the drop curtain to the point *b* and inclines steeply down to the point *c* where it will pass behind the wing 2. The attendant pushes 100 the dummies up from the point *a* to the point *b* and at the proper time starts the dummy down toward the point *c*. While passing down this steep incline the dummies will acquire a very high velocity and dash quickly 105 along the portion 1 of the track. As will be seen by reference to Fig. 3 the lower edge 13 of the curtain 4 is formed of light flexible material to allow of the passage of the arms 11 under the curtain while the cars move 110

along the portion 1 of the track. The real cars are used only at the beginning of the race and the dummies are thereafter employed.

5 On the curtain 4 is painted a suitable landscape which is also continued on the wings 2 and 2^a, and a track 14 is so outlined through the landscape as to appear to be a continuation of the portion 1 of the track 10 on the stage. The effect of a lighted track is produced by forming openings 15 along the edge of the outlined track and behind these openings are arranged lamps 16. In order to give the effect of distance these 15 openings are made gradually smaller to what is apparently the most distant point of the track. In order to give the impression that cars are passing along the track 14 a moving picture apparatus 17 is preferably 20 employed. A film 18 such as shown in Fig. 5 is so produced from a real auto race in a manner well known in the art, that when thrown on the curtain 4, automobiles or other objects so photographed will appear 25 to be moving along the track 14. After the film has been taken all parts except where the cars appear are rendered opaque, so that only the cars will appear on the curtain. It will be understood that the cars which are 30 photographed will be distinctively marked to correspond with the real cars and dummies used on the stage, so that the effect will be heightened.

In lieu of the moving picture apparatus, 35 the desired effect may be produced by making the part of the curtain on which the track is outlined of translucent material and throwing onto that portion shadows of the cars, the shadows being caused to move 40 along the track. The shadows may be produced by painting the outlines of the cars on the glass fronts 19 of boxes 20, in which are arranged lamps 21. These boxes are moved in paths corresponding to the track 45 and the sharpness of the shadows are decreased or increased to give the effect of the cars moving away from or toward the audience by moving the light or glass 19 relative one to the other. Or the glass and 50 lamp may be relatively stationary and the box as a whole moved from and toward the curtain.

In lieu of painting the outlines of an 55 automobile or other object on the glass front of the box 20, a miniature skeleton 31 of the object so constructed that its parts may be operated by a suitable motor, is arranged in the box in front of the lamp, as shown in Fig. 7. This apparatus may be operated as 60 stated in connection with the construction shown in Fig. 6.

When it is desired to show an accident in the race a collapsible dummy 22 resembling closely in appearance is employed. 65 During the race this dummy is placed on

a platform 23 extending laterally from the portion 3 of the circular track and preferably adjacent to its highest part. At the proper time one of the dummies 5, 7 or 9 is shifted from the track and the collapsible dummy substituted therefor. After the preceding car has passed the judge's stand 24, the post 25 which is hinged at its lower end to a suitable support drops over across the track onto a block 26 adapted to be raised at the proper time to support the post. As the dummy 22 strikes the post it will collapse giving a very realistic reproduction of an accident. In order to heighten this effect, wires 27 and 28 are connected respectively to the rear end of the collapsible car 22 and also the rubber manikin 29 seated in the car. As shown in Fig. 2 these wires pass the edge of the curtain 4, which is stiffened to prevent distortion, across the front of the curtain and over pulleys 30, behind the representations 31 of a grandstand sufficient weights are attached to the wires to keep them under tension as the dummy 22 moves from the platform 23 to the point where the accident occurs. As the dummy strikes the fallen post and collapses, an attendant gives a strong pull to the wires and jerks the manikin behind the grand stand and causes the car to turn a complete somersault.

While for convenience in describing and showing my improvement, I have adapted a track suitable for auto vehicles it will be readily understood by those skilled in the art that a course or way for any kind of vehicle may be employed and hence the term track is used herein in its broadest sense.

It is characteristic of the means employed for producing the illusory effects on the curtain, it is capable of conveying the impression of movement of the objects but also of their movements independent one of the other.

To produce the effect of a race the order of movement of the objects should be changed, so as to give the impression of one object passing the other. The platform 23 forms a convenient means for effecting such change of position. As soon as car moves into line with the platform its propelling arm is detached, and moved to one side and the car moved onto the platform. The other car or cars are then moved ahead, the first car moved back onto the track and its propelling arm connected thereto. Of course these changes of position will be reproduced when making the film and shown on the curtain.

In lieu of the manikin a real person or other object may be placed in the collapsible car to be suddenly removed at the time of the accident. It will be understood that the portion of the stage in front of the curtain 4 is to be brightly illuminated by suitably arranged lights, which however should be

so shaded as to leave the curtain sufficiently obscured so as to bring out sharply the picture or shadow thrown thereon as hereinbefore stated.

5. I claim herein as my invention:

1. In an apparatus for producing stage effects, the combination of an endless track arranged on a stage, objects adapted to move along said track, a curtain arranged to conceal a portion of the track and having outlined thereon a representation of the portion of the track concealed by the curtain, and means for producing the illusion of objects moving along the track outlined on the curtains.

10. 2. In an apparatus for producing stage effects, the combination of an endless track arranged on a stage, objects adapted to move along said track, means for imparting an increasing speed to the objects as they move along a portion of the track, a curtain arranged to conceal a portion of the track and having outlined thereon a representation of the portion of the track concealed by the curtain, and means for producing the illusion of objects moving along the track outlined on the curtain.

15. 3. In an apparatus for producing stage effects, the combination of an endless track arranged on a stage, objects adapted to move along said track, means for independently propelling said objects, a curtain arranged to conceal a portion of the track and means for producing on the curtain the effect of the continued movement of the objects when the latter have moved onto the concealed portion of the track.

20. 4. In an apparatus for producing illusory effects, the combination of an endless track arranged on a stage, objects adapted to move along said track, means for propelling said objects independently one of the other, a curtain arranged to conceal a portion of the track, and means for producing on the curtain the effect of the continued and independent movement of the objects when the latter have passed from in front of the curtain.

25. 5. In an apparatus for producing stage effects, the combination of an endless track having a portion thereof elevated, objects movable along said track, means for propelling the objects along the track, a curtain arranged to conceal the elevated por-

tion of the track, and means for producing on the curtain the effect of the continued movement of the objects when the latter have passed from in front of the curtain.

6. In an apparatus for producing stage effects, the combination of a track arranged on the stage, objects adapted to move along said track, a collapsible representation of one of said objects adapted to be substituted for the latter and an obstruction adapted to be shifted into the path of movement of the collapsible dummy.

7. In an apparatus for producing stage effects, the combination of a track arranged on a stage, objects adapted to move along said track, a collapsible dummy of one of said objects and adapted to be substituted therefor, a manikin carried by the collapsible dummy, an obstruction adapted to be shifted into the path of movement of the dummy and wires connected to the dummy and manikin for shifting the manikin and dummy when the latter strikes the obstruction.

8. In an apparatus for producing stage effects, the combination of an endless track arranged on a stage, objects movable along said track, means for independently propelling said objects detachably connected thereto, and a platform extending from the track for the reception of an object when it is desired to change the order of movement of the objects.

9. In an apparatus for producing stage effects, the combination of means for producing on the stage certain predetermined actions or movements, and a moving picture apparatus for producing the illusion of the continuation of such actions or movements after the objects involved in such actions or movements have passed out of sight of the audience.

10. The method of producing stage effects, which consists in forming moving picture films of scenery, and objects moving through such scenery, depicting the scenery on a curtain, blotting the scenery from the film and projecting the moving objects on the curtain.

In testimony whereof, I have hereunto set my hand.

HOWARD THURSTON.
